JOHN T. STONEY, OF CLEVELAND, OHIO, ASSIGNOR TO THE STONEY FOUNDRY ENGINEERING & EQUIPMENT CO., OF CLEVELAND, OHIO, A CORPORATION OF OHIO.

CLAMP MEANS.

1,410,619.

Specification of Letters Patent. Patented Mar. 28, 1922.

Application filed August 12, 1921. Serial No. 491,706.

To all whom it may concern:

Be it known that I, JOHN T. STONEY, a citizen of the United States, residing at Cleveland, county of Cuyahoga, and State 5 of Ohio, have invented a new and useful Clamp Means, of which the following is a specification.

My invention relates to clamp means adapted to firmly lock and readily unlock 10 objects to or from each other.

The object of my invention is a simple and efficient clamp means which is easily applied removed, which firmly locks the members to which it is applied, which readily releases these members when so desired, and which does not get out of order easily.

I attain this object by the mechanism illustrated in the accompanying drawing in which Fig. 1 is a side view of a clamp; Fig. 20 2 is an end view of Fig. 1; Fig. 3 is a side view of a clamp applied to a pair of flasks having hooks; Fig. 4 is an end view of Fig. 3; Fig. 5 is a side view of a clamp applied to a pair of flasks having tubes; and Fig. 6 25 is an end view of Fig. 5.

Similar reference characters refer to similar parts throughout the views.

The clamp proper consists of the levers 10 and 11, and the pin 12.

The lever 10 has the prong 13 projecting from its main body at the upper end and terminates, at its lower end, in the ear 14 which has an opening for the pin 12.

The lever 11 has the prong 15 projecting from its main body at the lower end and terminates, at its upper end, into the ears 16 which have openings for the pin 12.

The pin 12 extends through all of the ears and slightly beyond them and is slightly riveted over at each end to retain it in place.

It is noted (Fig. 2) that the edges 17 and 18 of the levers 10 and 11 are in alignment and that one side of each ear projects outside of the main body of the levers. This is 45 for the purpose of permitting the clamps to be used in any position as illustrated in Figs. 3, 4, 5, and 6 for instance, and also to provide a pin of sufficient strength and sufficient material in the ears for strength 50 around the pin without encumbering the levers as a whole with unnecessary material.

The prongs 13 and 15, preferably, project from the main body of the levers substantially at right angles, but may be in-

clined inwardly when desirable as seen in 55 Figs. 3 and 4 for instance.

The levers themselves may be made of suitable lengths and it is preferred that both be of the same length from the center of the pin to the centers of the prongs. 60

The wedge 20 is taper and may be made of any suitable material and size.

The operation and application of the present invention is illustrated in two exemplifications in Figs. 3, 4, 5, and 6. 65

In Figs. 3 and 4, the levers have inclined prongs to hook over the lugs 21 and 22 on the flasks 23 and 24. This inclination of the prongs here prevents slippage of the prongs on the lugs and consequently slippage of 70 the clamp as a whole endwise.

The clamp is here applied with the edges 17 and 18 away from the flasks and the prongs are hooked over the lugs. The wedge 20 is now driven in between the flasks and 75 the levers to hold the clamps unto the lugs and clamp the flasks to each other.

When the wedge is so driven in, the central portion of the clamp moves outward while the prongs move inward, similar to 80 the action of a toggle joint, and the flasks are firmly clamped and locked to each other.

In Figs. 5 and 6, the prongs project substantially at right angles from the main 85 body of the clamps and hook into the tubes 25 and 26 on the flasks 27 and 28. The clamp is here applied with the edges 17 and 18 toward the flasks and the projecting portion of the ears away from the flasks and 90 is also applied reversed from the position shown in Figs. 3 and 4. The wedge 20 is driven in as above set forth, one face thereof bearing against the flasks while the opposite face bears against the circular portion of the ears. 95

When the wedge is so driven in, the central portion of the clamp moves horizontally outward as above set forth and both flasks are firmly clamped and locked to each other. 100

This clamp may be applied in different positions, upside-down, or end for end (as partially illustrated in Figs. 3, 4, 5, and 6) as may best suit any general or particular purpose. 105

When the clamp is applied as seen in Figs. 5 and 6 for instance, the upper and lower edges of the wedge bear against the edges 17

and 18, respectively, when the clamp is applied, the wedge will thereby be held in position up and down although there usually is sufficient friction between the wedge and the flasks to prevent such up and down slippage of the wedge. However, the leverage of the toggle joint is here reduced since the wedge acts against the levers at a point between the prongs and the pin 12.

10 When the clamp is applied as seen in Figs. 3 and 4 for instance, the wedge acts against the circular portion of the ears whereby the fullest possible leverage is attained but the wedge is here not guided by the levers. 15 There is little danger, however, that the wedge will slip out of place since considerable friction exists between the flasks and the wedge to retain the same in position.

It will be seen that this clamp means is 20 efficient since it firmly clamps and locks the flasks together so that they can be moved about without danger of coming loose and since it is easily and quickly applied or removed, and since it may be applied in different 25 positions; that this clamp means is simple of construction and not liable to get out of order; and that this clamp means is inexpensive of first cost.

I claim:—

30 1. A clamp means comprising a clamp composed of two levers hinged together and each provided with means for engaging an article, and means for forcing the central portion of said clamp outward in a manner similar to a toggle joint.

35 2. A clamp means comprising a clamp composed of two levers hinged together and each provided with an angularly projecting

prong, and means for forcing the central portion of said clamp outward in a manner 40 similar to a toggle joint.

3. A clamp means comprising a clamp composed of two levers hinged together and the outer end of each provided with means for engaging an article and the inner ends 45 of both provided with ears and one side of each lever in alignment with the corresponding side of the other lever when both levers are fully extended, and means for forcing the central portion of said clamp outward in 50 a manner similar to a toggle joint.

4. A clamp means comprising a clamp composed of two levers hinged together and the outer end of each provided with means for engaging an article and the inner ends 55 of both provided with ears diametrically larger than the main body of the levers and extending beyond this main body on one side only, and means for forcing the central portion of said clamp outward in a manner 60 similar to a toggle joint.

5. A clamp means comprising a clamp composed of two levers hinged together and each provided with a prong projecting from its main body at an inner angle of less than 65 90 degrees, and means for forcing the central portion of said clamp outward in a manner similar to a toggle joint.

6. The combination with a pair of flasks, of a clamp composed of two levers hinged 70 together and provided with means for engaging said flasks, and a wedge between the walls of said flasks and the central portion of said clamp to force this central portion outward and lock said flasks to each other. 75

JOHN T. STONEY.
